(57) **CLAIM**

The ornamental design for a shoe sole, as shown and described.

DESCRIPTION

FIG. 1 is a left front perspective view of the present invention.

FIG. 2 is a left side elevational view thereof.

FIG. 3 is a right side elevational view thereof.

FIG. 4 is a bottom plan view thereof.

FIG. 5 is a top plan view thereof.

FIG. 6 is a front elevational view thereof; and,

FIG. 7 is a rear elevational view thereof.

No claim is made to the upper construction shown by use of dashed-shadow lines. The upper is shown as an environmental aid only. Identified sections of the shoe sole in multiple figures marked by dashed-shadow lines also form no part of the claimed design and are provided for environmental assistance only. No claim is made to the portions of the shoe sole not shown in solid lines, and the remaining unshaded portions of the shoe sole are not claimed.
